United States Patent Office

Des. 210,668

Patented Apr. 2, 1968

210,668

TELEPHONE HANDSET

George M. Janda, Westchester, Ill., assignor to Automatic Electric Laboratories, Inc., a corporation of Delaware

Filed Apr. 4, 1967, Ser. No. 6,516

Term of patent 14 years

(Cl. D26—14)

FIG. 1

FIG. 2

FIG. 3

FIG. 4

FIG. 1 is a perspective view of a telephone handset showing my new design;

FIG. 2 is a plan view of the handset as seen from the back;

FIG. 3 is a side elevational view of the handset; and

FIG. 4 is a plan view of the handset as seen from the front.

The dominant features of my design reside in the portions shown in full lines.

I claim:

The ornamental design for a telephone handset, substantially as shown and described.
